UNITED STATES PATENT OFFICE

NATHANIEL M. LURRAIN, OF WOODSIDE, NEW YORK

COLLAPSIBLE PICTURE FRAME

Application filed October 14, 1932. Serial No. 637,838.

This invention relates to a combined collapsible easel and collapsible picture frame, the object being to provide a collapsible or knockdown easel which may be knocked down and rolled for shipment and at the same time provide a picture frame structure which may be disassembled and rolled with the easel when the same is to be shipped or stored.

Another object of the invention is to provide a collapsible frame which may or may not be part of an easel, the structure being such that the corner structures interlock in such a manner as to hold the parts together by friction while permitting ready disengagement at any time.

A further object, more specifically, is to provide a knockdown picture frame which may be made out of paper or sheet metal and cut and folded to produce a frame structure having interlocking corners with the interlocking portions hid.

In the accompanying drawings—

Figure 1 is a side view of an easel or picture frame disclosing an embodiment of the invention;

Figure 2 is a front view of the structure shown in Figure 1;

Figure 3 is a perspective view showing the easel and frame knocked down and rolled ready for storage or shipment;

Figure 4 is an enlarged fragmentary sectional view through Figure 2 on the line 4—4;

Figure 5 is an enlarged front view of one of the corners of the frame shown in Figure 1, the parts being shown broken away for illustrating the interior structure;

Figure 6 is a sectional view through Figure 5 on the line 6—6;

Figure 7 is a perspective view of one end of one of the frame pieces disclosing certain features of the invention;

Figure 8 is a fragmentary perspective view of another frame piece arranged to telescope over part of the frame piece shown in Figure 7.

Figure 9 is a perspective view of the end shown in Figure 7, the parts being shown in open position;

Figure 10 is a perspective view similar to

Figure 7 but showing a modified construction;

Figure 11 is a perspective view similar to Figure 9 but showing the structure illustrated in Figure 10;

Figure 12 is a perspective view of a modified form of one end of one of the frame pieces; and

Figure 13 is a perspective view of one end of a second frame piece, the same being adapted to interlock with the structure shown in Figure 12.

Referring to the accompanying drawings by numerals, 1 indicates an easel as a whole, said easel having a sheet 2 on which pictorial members are arranged or other information. The sheet 2 is provided with a rigid bar 3 at the upper end and a rigid bar 4 at the lower end. The base 5 is connected at one end to bar 4, said base accommodating the brace 6 which has one end fitted into a suitable notch in bar 3 and the other end sharpened and fitted into one of the corrugations 7 in the base 5.

A metal anchor 8 is connected at one end to brace 6 and at the other end is removably connected to base 5 by pin 9. This structure presents an easel structure which is adapted to display advertising or other matter but is more or less unfinished. In order

to secure a desired finish or pleasing appearance, a frame 10 is arranged around the edge of the sheet 2, this frame being provided with a frame bar or part 11 secured to the lower edge of the sheet 2 by adhesive, as shown in Figure 4, whereby it is really a permanent part of the easel. The frame parts or bars 12, 13 and 14 are then assembled and held in place by the friction of the various parts. The rear of the bars or parts 12, 13 and 14 rest against the sheet 2 but are not secured thereto. The end bar or part 11 and the top bar or part 14 are made identical and as shown in Figure 8. Only one end of the bar is shown in Figure 8 but it is to be understood that the opposite end is the same except that the angle is reversed in order to match the angle of the bar 12. It will be noted that each of the bars 11 to 14 inclusive

is formed from sheet material as, for in-

stance, cardboard, paper or even from this sheet metal. The particular structure shown in the drawings has been made from paper or cardboard covered with an ornamental paper so that the inclined or beveled face 15 will be more or less ornamental. Thin paper simulating oak or other wood can be readily secured to the other paper or cardboard and then the other paper or cardboard cut out 10 into blanks which are folded to form the structures shown in the drawings.

As illustrated in Figure 8, the bar 14 is provided with a base 16 which is bent at right angles forming an edge 17, which edge in turn is bent to form an inclined front face 15, and this part of the bar 14 is bent at 19 to form the reinforcing and holding flange 20 which is secured to base 16 by adhesive. The front face 15 is cut away at both ends, as indicated by the line 21. Preferably the flange 20 is also cut away in like manner but the base extends to the corner projection at 22 which is adapted to slide over the end of the base 23 of bar 13. To connect the parts together they are arranged as shown in Figures 7 and 8 and then the bar 14 of Figure 8 is merely forced over the folded connecting block 24, and the parts will appear as shown in Figure 2.

Both ends of bar 13 are alike and both bars 12 and 14 are designed so that the structure 5 shown in Figure 7 will apply to both ends and also to both bars. As illustrated in this figure, and also in Figure 9, the bar 13 is provided with a base 23 which extends beyond the end of the bar and is creased along lines 25, 26 and 27 so that the parts may be folded along these creases until the block 24 is formed. Base 23 merges into a back edge member 28 which in turn merges into a face member 29, which face member is bent at 30 to form the bracing and holding flange 31, which flange preferably extends to the point substantially in contact with the edge strip 28. Flange 31 is preferably held in place by adhesive, although the folded extension or box 24 is not glued.

When the parts are arranged as shown in Figure 7 they are in position for use, and the bar 14 has its ends slid thereover to complete the corner of the frame 10. It will be noted that by reason of the edge 17, and also the strip 28, the outside of the frame 10 is of ample depth while the face members 15 and 29 are inclined or beveled to produce a pleasing appearance. Consequently, there is no front strip but merely a bending as, for instance, along the lines 19.

If desired, instead of arranging the parts as shown in Figure 9, they could be arranged as shown in Figs. 10 and 11. As illustrated particularly in Figure 11, the back 32 is provided with an extension which is folded to form the box 24, which coacts with flange 34

to form a rear edge when the parts are folded as shown in Figure 10. The front panel 35 is cut away at 36 so that when the box 24 is folded and flange 34 is folded over flange 33, the box 24 will be exposed through the cut out portion 36 as illustrated in Figure 10.

Figures 12 and 13 show another form of the invention, wherein the bars 13' and 14' are substantially of the same structure as in the other forms except at the ends.

As shown in Figure 12, the front panel 29 is cut away at 37, while on the base 23 is arranged a pair

of spacing strips 38 and 39 and a locking strip 40 whereby a passageway 41 is provided. Bar 14' is the same as bar 8 except the end

where it is cut away at 42. The base is cut away at 43 whereby a straight tongue 44 is provided, said tongue being adapted to slide

into the passageway 41 until the cut away edge 42 engages the cut away edge 37. The

friction of tongue 44 in the passageway 41 acts to lock the parts together in the same

way that the friction of the box 24 acts against the corresponding parts on bar 14. While

as a preferable structure the bar 11 is glued or otherwise permanently secured to the bottom edge of sheet 2, it can be made separate

and the frame rests against the sheet 2, or the frame used in some other place or manner, the use not changing the particular structure of the corner pieces or of the body portions of the respective frame parts or bars.

However, it is very desirable to glue the bottom bar 11 to the bottom of sheet 2 when the frame is being used with the easel 1. While

the parts are arranged as shown in Figures 1 and 2 the matter on sheet 2 is nicely displayed within the frame, all parts being supported by the easel structure. When it is desired

to store or ship the parts, the frame bars 12 and 13 are pulled away from the other bars and then arranged in parallel relation with the bar 11. The brace 6 and associated parts

are then disconnected and placed parallel with and near bar 11. The base 5 is swung on its pivotal connection 5' until it is parallel with bar 4. The parts are then rolled to the

position shown in Figure 3, after which they are tied or otherwise held in position until

further use is desired. It has been found that after the parts have been rolled as in Figure 3 they may be placed in an ordinary composite board tube and stored or shipped in this

manner without injury. After the parts have been shipped to the desired destination a person merely unrolls the easel and sets same up, as shown in Figure 1. Afterwards the side pieces or bars 12 and 13 are placed in

position by sliding over the box 24 of bars 11 and 14 and the frame is in operative position.

As the parts are merely set in position and slid out of position, it will be evident that all the parts are held together by friction,

and that the parts may be quickly assembled

and disassembled without the use of tools and without injury to the parts.

I claim—

1. A collapsible picture frame comprising a plurality of bars each bar being formed of sheet material folded to produce an inclined face, a base and back wall arranged at right angles to each other, and means having a plurality of friction surfaces for frictionally securing said bars together, said means being arranged at the respective ends of the respective bars.
2. A collapsible picture frame comprising a frame structure having side bars and top and bottom bars, each of the bars being formed hollow and triangular shape in cross section, certain of said bars having one wall cut away at each end and the others of said bars having a folded extension at each end presenting friction retaining boxes adapted to be inserted into the ends of other bars for holding the respective bars together in assembled relation.
3. A picture frame formed of pasteboard and provided with identical corner structures, each corner structure including a chamfered end in the front face of the respective adjacent bars, and a folded friction box extending from one of the bars and slidingly fitting into the other bar.
4. A collapsible picture frame comprising a plurality of bars, each bar being formed of sheet material folded to present a structure triangular in cross section, said bars at their respective corners having an incline or surface chamfered so as to produce a proper contact when the bars are connected together, one of the bars at the point of connection having an extending base portion overlapping the base of the other bar, and said other bar having a folded extension presenting a friction box slidingly fitted into the first mentioned bar for frictionally holding the bars together.
5. In a collapsible picture frame formed with a plurality of bars, certain of said bars being formed of sheet material folded into a shape which is substantially triangular in cross section, said last mentioned bars at the ends having one surface chamfered and the other surface provided with an extension folded so that part thereof will be beneath the chamfered surface and positioned to present a friction box for receiving a mating member.
6. The combination with an easel having a bracing structure including a removable bracing rod, of a picture frame formed of four bars removably connected at their respective ends, one of said bars being connected permanently to the easel.
